UNITED STATES PATENT OFFICE.

RUSH E. MARTIN, OF OSHKOSH, WISCONSIN.

TYPE-WRITING MACHINE.

No. 917,959.

Specification of Letters Patent.

Patented April 13, 1909.

Application filed March 25, 1908. Serial No. 423,210.

To all whom it may concern:

Be it known that I, RUSH E. MARTIN, a citizen of the United States, residing at Oshkosh, in the county of Winnebago and 5 State of Wisconsin, have invented certain new and useful Improvements in Type-Writing Machines, of which the following is a specification.

My invention relates to improvements in 10 type-writers, and especially to improvements in that class of typewriting machines having a type basket and a single-letter type movement, such as the Remington and Densmore machines, and the objects of my 15 invention are to increase the speed of execution and the utility of typewriting machines. I achieve these results by adding to the ordinary mechanism of said class of typewriting machines, further mechanisms 20 adapted to print syllables of three letters or words or syllables of two letters, and provide a space, syllables of four letters or words or syllables of three letters and provide a space, syllables of five letters or words 25 or syllables of four letters and provide a space, syllables of six letters or words or syllables of five letters and provide a space, and further, if desired. It is obvious that where an entire word or terminal syllable is 30 printed the space should be added by the escapement—as hereinafter stated. I thus print the shorter words of plural letters, or a word and provide a space bodily by a single impact of the type.

35 In the drawings illustrating my device:— Figure 1 is a plan view of my device; Fig. 2 is a side elevation illustrating the operation of my invention, and Fig. 3 is a rear view of the same. Fig. 4 is a side view of 40 one of the key-levers operating the single-letter escapement. Fig. 5 is a side view of one of the key-levers operating the word-escapement. Fig. 6 is a front view, and Fig. 7 a side view of the escapement 45 frame. Figs. 8 and 9, 10 and 11, 12 and 13, 14 and 15 are side and front views of the respective escapements. Fig. 16 is a detail view of one of the type heads.

In my invention I construct the basket 50 much larger than the ordinary basket used in said class of machines, and I arrange the single-letter types at the rear of the basket

and they are operated in the same manner and by the same key-board as is ordinarily used in such class of machines. The type-heads carrying the words are arranged at the front part of the basket. The space is entirely effected by the escapement. I provide two words on each word type-head so that the upper word may be printed by the 60 use of the ordinary shift key.

In my invention I arrange further banks or sets of keys outwardly and rearwardly from the ordinary key-board, and having, upon the keys, words to correspond with 65 the word type-heads in the basket.

The arrangement of the key-board may be adapted to suit the convenience of the operator or to the particular class of business for which the particular machine is 70 desired. In the newspaper business certain words are most frequently used and the key-board can be arranged accordingly. In court and law work a different set of words is most frequently used and the key-board 75 can be arranged accordingly; and the same applies to other classes of business such as railroad, grain, lumber, paper, etc.

A further object of my invention is to provide escapements relative to each class 80 of words that may be operated by key-levers to move the paper the proper distance to allow the type-head to print the desired length of word and provide the desired space.

My invention operates preferably in connection with the ordinary mechanism of a typewriter of said class. The key-levers printing the words are preferably entirely independent of the ordinary key-levers 90 which print the single letters in such typewriters.

Referring to the drawings by numerals, 2 represents the frame and 3 the basket of the machine.

4, 4 etc. represent single-letter keys, and 5, 5, 5, etc. represent word keys; 6, 6, 6 etc. represent the ordinary key-levers used in machines of said description, and 7, 7, 7, etc. represent the word key-levers. Each key-lever 7 rocks upon the fulcrum rod 8, which extends through an eye, 8' in a lug 9 on the key-lever for that purpose. The fulcrum rod 8 is supported by the standards

9'-9' attached to the frame. Each key-lever 7 is provided with a lug 15, having a U-shaped slot 16.

17-17 etc. represent escapement supporting frames which slide upward and downward in perpendicular guides 34, 34, 34 etc. provided at each side.

In Fig. 2 the side rail of each frame is cut away to show the bottom rods 18, 18, 18 etc. Downward pressure upon the key 5 rocks the key-lever 7 upon the fulcrum rod 8 and raises the opposite end. The rods 18, 18, 18 etc. pass through the U-shaped slots 16, 16, 16, etc. and are carried upwardly at each pressure on a word key.

19 represents the top-rail of the frame and supports one of the escapements, as 22.

In my invention I arrange the frames 17, 17 etc. to the rear of the general mechanism 20 of the machine, and I suspend the ratchet bar 24 by hangers 25, 25 which are rigidly attached to the release lever rod 26, said rod being journaled to the carriage frame at 27, 27. The holding ratchet wheel 28 is 25 keyed to the end of the shaft 29 which carries the single-letter escapement 30. By this construction I do not disturb the action of the regular mechanism applied to the single letters, and am able to locate the 30 entire word escapement mechanism to the rear of the regular mechanism. The ratchet bar 24 is detained by engagement of one of its teeth with a corresponding tooth of the holding ratchet wheel 28. When released 35 from this engagement the bar 24 is moved with the carriage by the ordinary carriage spring 37, provided for that purpose.

By downward pressure upon one of the keys 5, one of the escapements as 20 is 40 brought upwardly into engagement with the teeth upon the ratchet bar 24 and raises said bar free from the holding ratchet wheel 28. The carriage spring, as 37, aforesaid, then operates to move the ratchet bar 24 45 laterally and revolves one of the escapements, as 20, in engagement therewith, until the lug 31 strikes against the stop 32. At the same time the downward pressure upon the key 5 operates the type-bar 33 and 50 forces the type-head 14 upwardly against the platen. This operation will print syllables of three letters or words of two letters and provide one space. As soon as the key 5 is released the escapement, as 20, 55 drops by gravity out of engagement with the ratchet bar 24, and said ratchet bar 24, by gravity and by a spring such as is used in the ordinary mechanism, returns into engagement with the holding ratchet wheel 28. 60 The spring 35 operates to revolve the escapement back to its original position, the lug 31 impinging against the stop 36. In the same manner the escapements 21, 22 and 23 may be operated to print syllables or words

of four letters, or of three letters and provide 65 a space; syllables or words of five letters, or of four letters and provide a space; syllables or words of six letters, or of five letters and provide a space. For that purpose the escapement 20 is provided with three teeth, 70 the escapement 21 with four teeth, the escapement 22 with five teeth, and the escapement 23 with six teeth, and the escapement 75 wheels revolve a corresponding distance between the respective stops 32 and 36. In the operation of the escapements, as 20, against the ratchet bar 24 the first engaging tooth upon the escapement is always farthest to the right and uppermost when brought to the engaging position, as shown 80 in the drawing Fig. 3.

By reason of the arrangement of the frames in the guides 34, 34, 34, etc. it is necessary to off-set the escapement supporting standards 39, 39, 39 etc. at different degrees 85 (except one of the escapement supporting standards 39, supporting escapement 21) each of said standards being offset at a proper degree to bring the escapement, as 22, in perpendicular alinement with the 90 ratchet bar 24.

It will be observed that the word type-bars as 33 must be arranged in the basket in front of the fulcrum rod 8 so that the downward pressure upon a key 5 will operate a type-bar bearing a word type, as 14. The eyes 8' are located in top lugs 9 so that the fulcrum rod 8 extends above the ordinary key-levers of the machine and does not interfere with their operation. 100

In the operation of my invention the operator by pressing downwardly upon one of the keys 5 actuates the type-head 14 upwardly toward the platen, and at the same time by the rocking of the key-lever 7 upon the fulcrum rod 8 the opposite end of the key-lever 7 is raised and carries with it one of the escapement supporting frames. The full downward pressure upon the key causes the escapement, as 22, to engage and raise 110 the ratchet bar 24. The strength of the carriage spring 37 is much greater than the strength of the escapement spring 35. The carriage is moved horizontally by the tension of the carriage spring 37, compressing 115 the spring 35 until the lug 31 strikes against the stop 32. A space is then afforded for the striking of the word type-head 14 against the platen. As soon as key 5 is released the escapement, as 20, drops by 120 gravity out of engagement with the ratchet bar 24, and the ratchet bar 24, by gravity and spring pressure, descends into reengagement with the holding ratchet wheel 28.

The operation of my invention does not 125 in any manner interfere with the operation of the single-letter keys.

The rods 18, 18, 18 etc. extend through all

of the U-shaped slots 16, 16, 16 etc. of each 5
respective series of word key-levers. When
a word key-lever is operated it raises the
escapement frame, as 20, and the rod 18 is
permitted to travel in the U-shaped slots 16,
16, 16, etc. of all other word key-levers in
said series without interfering with or actu-
ating them in any way. For this purpose
the slots are made wider at the top so as to
10 give a free action to said rod 18.

The U-shaped slots 16, 16, 16, etc. are of
sufficient depth to permit the operation of
the rods 18, 18, 18 etc. below the range of
15 the ordinary single-letter key-levers, and
likewise to permit of the operation of the
ordinary single-letter key-levers without
coming into contact with said rods 18, 18,
18, etc.

Having thus described my invention what
20 I claim to have invented and desire to se-
cure by Letters Patent is:—

1. In a typewriting machine of the class
described, the combination with the ordi-
nary mechanism of the machine of one or
25 more series of word key-levers, a fulcrum
rod extending through eyes in the key-
levers, escapement supporting frames, per-
pendicular guides for the frames, dependent
30 lugs integral with the key-levers, near the
rear ends, and having U-shaped slots which
inclose the base rod of the escapement sup-
porting frame, a toothed escapement wheel
carried by each escapement supporting
35 frame, adapted to engage and raise the or-
dinary ratchet bar of the machine and re-
volve a determinate distance, a spring to
return said escapement wheel to its normal
position when not in engagement, type-bar
40 levers linked to the front portion of the
key-levers, type-bars operating upwardly
thereby, type-heads carried by said type-
bars, said type-heads having a plurality of
letters in horizontal alinement, substantially
45 as shown.

2. In a typewriting machine of the class
described, the combination with the ordi-
nary mechanism of such a machine of sev-
eral series of word key-levers fulcrumed
rearwardly of the center of the basket and
50 adapted to rock upon a fulcrum rod extend-
ing through eyes in top lugs integral with
the key-levers, an escapement supporting
frame for each series of key-levers, perpen-
pendicular guides for the frames, dependent
55 lugs integral with the key-levers in each
series, near the rear ends, having U-shaped
slots which inclose the base rod of the cor-
responding escapement supporting frame,
toothed escapement wheels, carried by the
60 escapement frames, each adapted to engage
and raise the ordinary ratchet bar of the
machine and revolve a determinate distance,
springs to return the escapement wheels to
their normal positions when not in engage-

ment, type-bar levers linked to the front 65
portion of the key-levers, type-bars operat-
ing upwardly, type-heads carried by said
type-bars, said heads having a plurality of
letters in double horizontal alinement to cor-
respond with each series of key-levers and 70
with the letters indicated upon the face of
the word keys, substantially as shown.

3. In a typewriting machine of the class
described, the combination with the ordi-
nary mechanism of the machine, of a word 75
key-lever, a fulcrum rod extending through
an eye in the key-lever, an escapement sup-
porting frame, a perpendicular guide for
the same, a lug on the key lever, near the
rear end, and having a slot inclosing the 80
base rod of the escapement supporting
frame, a toothed escapement wheel carried
by the escapement supporting frame adapted
to engage and raise the ordinary ratchet bar
of the machine and revolve a determinate 85
distance, a spring to return said escapement
wheel to its normal position when not in
engagement, a type bar lever linked to the
front portion of the key-lever, a type bar
operated upwardly thereby, a type head car- 90
ried by said type bar, said type head having
a plurality of letters in a horizontal aline-
ment, substantially as shown.

4. In a typewriting machine of the class
described, toothed escapement wheels in 95
combination with the ratchet bar, means for
raising said escapement wheels into engage-
ment with the ratchet bar and raising the
bar and tension springs to provide a return
revolution of the escapement wheels when 100
lowered from the bar, substantially as shown
and described.

5. In a typewriting machine of the class
described, the combination with a ratchet
bar, of a series of toothed escapement wheels, 105
means for raising each of said escapement
wheels into engagement with the ratchet bar
and raising the bar, tension springs to pro-
vide a return revolution of the escapement
wheels, when dropped from the bar, and 110
word-keys in conjunction with the operating
means indicating the corresponding escape-
ment wheels substantially as shown and de-
scribed.

6. In a typewriting machine, a plurality 115
of syllable or word keys, an escapement
mechanism including a rack bar, and toothed
escapement wheels arranged for co-operation
with the rack bar to lift the same and for
actuation through the medium of the said 120
keys, the said wheels having teeth corre-
sponding in number to the number of let-
ters upon the respective keys.

7. In a typewriting machine, a plurality 125
of plural letter keys, an escapement mech-
anism including a rack bar, toothed escape-
ment wheels, supports for the wheels, the
said supports being arranged for actuation

through the medium of the said keys to bring the escapement wheels into coöperative relation with respect to the rack bar, and means upon the support for each wheel 5 for limiting its revolution.

8. In a typewriting machine, a plurality of plural character keys, an escapement mechanism including a rack bar, toothed escapement wheels, supports for the wheels, 10 the said supports being arranged for actuation through the medium of the said keys

to bring the escapement wheels into coöperative relation with the rack bar, and stops upon the support for each wheel for limiting its revolution.

15

In testimony whereof I affix my signature, in presence of two witnesses.

RUSH E. MARTIN.
